UNITED STATES PATENT OFFICE.

JOHN BUTLER, OF ECHO, MINNESOTA, ASSIGNOR OF ONE-HALF TO AUGUST J. HINZ,
OF WOOD LAKE, MINNESOTA.

HAMMER-ACTION NAIL PULLER AND WRECKING BAR.

Application filed April 21, 1923. Serial No. 633,739.

To all whom it may concern:

Be it known that I, JOHN BUTLER, a citizen of the United States, residing at Echo, in the county of Yellow Medicine and State 5 of Minnesota, have invented certain new and useful Improvements in Hammer-Action Nail Pullers and Wrecking Bars; and I do hereby declare the following to be a full, clear, and exact description of the invention, such as will enable others skilled in the art to which it appertains to make and use the same.

This invention relates to a nail pulling bar or a wrecking bar. Such bars are now 15 commonly used for tearing apart boxes and similar structures and for withdrawing the nails from such boxes or other structure after said nails have been driven flush with the surfaces thereof.

20 It is an object of this invention to provide such a bar having a pair of claws, which can be readily sunk into the surfaces containing the nail, said bar being bent so that the same can then be rocked to lift the 25 nail.

It is a further object of the invention to provide such a bar, having a handle portion bent upwardly from one side of the said claws and having the portion at the other 30 side of said claws bent upwardly a short distance and formed as a hammer head, which head can be struck a blow to sink the claws into the surface containing the nail.

It is still another object of the invention 35 to provide such a bar having the claws thereon formed adjacent the apertures extending through the bar and also to provide a bar having a plurality of such apertures and pairs of claws thereon.

40 These and other objects and advantages of the invention will be fully set forth in the following description made in connection with the accompanying drawings, in which like reference characters refer to the same 45 parts throughout the different views, and in which

Fig. 1 shows a bar in side elevation partly in section together with an object containing a nail;

50 Fig. 2 is a view of the bar in side elevation in a different position, also showing a part of an object containing a nail;

Fig. 3 is a partial plan view of the bar; and

55 Fig. 4 is a vertical section thereof taken

on line 4—4 of Fig. 1 and shown on an enlarged scale.

Referring to the drawings, the device comprises a bar of cylindrical or other suitable shape having the major portion 1 thereof 60 forming a handle portion and extending upwardly, the upper end 2 of said bar being flattened to form a chisel or crow bar. The intermediate portion 3 of the bar is substantially rectangular in cross section and will 65 be referred to as the horizontal portion. The other end 4 of the bar is of cylindrical or other regular shape and is bent upwardly to form substantially the same angle with the horizontal portion 3, as does the handle 70 portion 1. An aperture or slot 5 extends vertically through the bar adjacent the bend of the portion 4 and on the handle side of said bend and another aperture or slot 6 extends vertically through the bar adjacent the 75 bend formed by the handle portion 1 and at the handle side of said bend. The slots 5 and 6 emerge at their upper end to form one common opening, as shown in Fig. 3, but are separated at their lower portions by the portion or web 7 extending between the same.

A pair of claws 8 are disposed at the rear of the aperture 5 and diverge to form a pointed triangular slit 9 communicating with said aperture and another pair of claws 10 extend 80 from the rear portion of the aperture 6 and diverge to form a triangular slit 11 communicating with said last mentioned said aperture. The claws 8 and 10 project below the bottom surface of the horizontal portion 90 3 of the bar and are formed with longitudinal edges 12 and beveled to form points as clearly shown in Figs. 1 and 2, the front surfaces of the claws or the surfaces toward the handle portion of the bar being concave and 95 extending rearwardly of the pointed ends thereof. The claws 10 are formed with a somewhat larger opening therebetween than the claws 8, so that a larger nail can be embraced in said opening.

In operation, the claws 8 and 10 are used for drawing headed nails or tacks and if the nails project above the surface in which they are driven, the bar can merely be moved along said surface resting on the claws. The 105 nail will then move through the slots 5 or 6 and the head thereof will be caught above the claws and the shank of the nail be disposed between the same. The bar can now be rocked toward the rear by raising the 110

handle portion 1 and the nail withdrawn whether the nail is embraced by the claws 8 or by the claws 10. If the nail is driven into the surface so that the head is flush with the surface or beneath the same, the bar is disposed with the claws adjacent the nail as shown in Figs. 1 and 2. The handle portion of the bar is held with one hand and the hammer portion 4 given a blow by means 10 of a hammer or other implement. The pointed claws will then sink into the surface and pass beneath the head of the nail, after which the bar can be rocked rearwardly and the nail withdrawn. As stated, the smaller 15 and shorter nails can be pulled by the claws 8, while the larger and longer nails can be pulled by the claws 10. It will be noted that the bar can be rocked to raise the claws 10 a much greater distance from the surface than the claws 8. If the nails are spaced the right 20 distance both of the pairs of claws may simultaneously be used. The portion 2 of the bar will be useful in prying objects apart and in getting under boards or other objects 25 to lift the same.

In the above description it is seen that applicant has provided a simple, efficient and rugged wrecking bar. The bar can easily be made from standard stock and 30 thus be inexpensively produced. The device has been successfully demonstrated in actual use and found to have great utility for the purpose intended.

It will, of course, be understood that various changes may be made in the form, details, arrangement and proportion of the parts without departing from the scope of applicant's invention, which generally stated, consists in such an article as shown and described and set forth in the appended 35 claims.

What is claimed is:—

1. A bar having one end formed as a hammer head and being bent upward a short 40 distance from said end, said bar having its other end bent upward a short distance from said first mentioned bend to form a handle portion, and a pair of downwardly extending nail-engaging claws formed below each 45 bend in the bar.

2. The structure set forth in claim 1, the nail-receiving ends of said claws extending toward the handle portion of the bar, said hammer portion being adapted to be struck 50 a blow to drive said claws into a surface to engage a nail lying flush with or below the said surface.

3. A nail-pulling and wrecking device 55 comprising a bar having an aperture extending vertically therethrough, diverging claws at one end of said aperture forming a triangular pointed slit, said claws projecting from the lower surfaces of said bar, whereby they can be driven into a surface 60 to engage under a nail head flush with said

surface, said bar terminating a short distance beyond the converging end of said claws and being bent upwardly and formed as a hammer head, the other end of said bar being bent upwardly adjacent said aperture 70 to form a handle portion, said hammer head being adapted to be struck a blow to drive said claws into said surface to engage under a nail head lying flush with or below said surface. 75

4. A bar having one end formed as a hammer head and being bent upward a short distance from said end, said bar having its other end bent upward a short distance from said first mentioned bend to form a handle portion, apertures extending vertically through said bar adjacent said bends and at the sides thereof toward the handle portion and a pair of diverging pointed claws adjacent that end of each aperture which is disposed toward said hammer head. 80

5. The structure set forth in claim 4, said claws projecting below the bottom surface of said bar, whereby they can be drawn into engagement with the nail head projecting 90 from the surface while resting on said surface.

6. A nail pulling device comprising a bar having a substantially horizontal portion, the handle portion bent upwardly from said horizontal portion, an aperture through the lower part of said handle portion, a pair of diverging claws projecting downwardly from the bottom surface of said bar adjacent the end of said aperture disposed away 100 from said handle portion and forming a pointed slit communicating with the said aperture, said claws having points projecting toward the handle end of said bar, the other end of said bar beyond said claws 105 being bent upwardly whereby a nail head projecting from a surface can be moved into said aperture to be engaged by said claws while the same rest on said surface.

7. A nail pulling and wrecking device 110 comprising a bar having an intermediate horizontal portion substantially rectangular in cross section, a comparatively short upwardly extending portion at one end thereof formed as a hammer head and a handle portion at the other end of said intermediate portion extending upwardly therefrom and terminating in a flattened edge, said bar having a pair of apertures extending vertically therethrough adjacent the bends in the 115 bar and at the handle portion side thereof, a pair of claws disposed adjacent each aperture and at the end thereof disposed toward the hammer head end of said bar, said claws projecting below the bottom surface 120 of the intermediate portion of the bar, diverging and formed with points projecting toward the handle end of said bar. 125

In testimony whereof I affix my signature,
JOHN BUTLER.
